UNITED STATES PATENT OFFICE.

LORENZO D. BENNER, OF GALESBURG, ILLINOIS, ASSIGNOR TO GEORGE C. ALDEN AND ALONZO C. CLAY, BOTH OF SAME PLACE.

CORN-PLANTER CHECK-ROWER.

SPECIFICATION forming part of Letters Patent No. 274,259, dated March 20, 1883.

Application filed July 31, 1882. (Model.)

To all whom it may concern:

Be it known that I, LORENZO D. BENNER, a citizen of the United States, residing at Galesburg, in the county of Knox and State 5 of Illinois, have invented certain new and useful Improvements in Corn-Planter Check-Rowers; and I do hereby declare the following to be a full, clear, and exact description of the invention, such as will enable others 10 skilled in the art to which it appertains to make and use the same.

This invention relates to improvements in attachments to corn-planters, for transferring motion from a knotted wire or cord to the seeding devices of the planter; and it consists in constructions and combinations hereinafter described, and set forth in the claim hereto annexed.

In the accompanying drawings, which illustrate my invention, Figure 1 is a top plan of a device embodying my invention. Fig. 2 is a plan seen from below. Fig. 3 is a sectional elevation in the line $x-x$ in Fig. 2. Fig. 4 is a perspective, partly in section, of a detail hereinafter referred to.

Referring to the drawings by letters, the same letter indicating the same part in the different figures, letters A represent four ordinary forked levers adapted to receive motion 30 from a knotted wire or tappet-wire, a, in the ordinary manner. The levers A are mounted on a short shaft, B, which is journaled in any suitable base-plate, C, and extends through said base-plate, and has on its lower end four cams, d d' d'' d''', which project in different horizontal planes from the shaft B and in about coincident radial positions with the levers A.

The cams d d' d'' d''' may be constructed in 40 various ways; but I prefer them formed about as shown in the drawings—that is, with enlarged outer ends, slightly rounded or curved.

E is an oscillating bar, pivoted at e, and has

a slot, F, near its mid-length portion, which slot receives the end of the shaft B and the cams 45 d d' d'' d'''. One of the side walls of the slot F contains grooves f f', and the other side wall contains grooves f'' f'''. The grooves f f' permit the cams d d' to pass without coming in contact with the bar E, and the grooves f'' f''' permit the cams d'' d''' to pass in a similar manner. The cams d d' d'' d''' come in contact alternately with alternate sides of the slot F, and thus give an oscillating movement to the 55 bar E, and while one cam is acting on the bar to move it in one direction the cam which projects in an opposite direction from the shaft B is passing through one of the grooves in said bar, to permit of the movement of said bar E, as hereinbefore described.

The bar E may be connected by any suitable rod, G, with the seeding devices of the planter, so that the oscillating movements of said bar will impart movement to said planter seed-slides. It will also be seen that the bar E may 65 be pivoted at either end.

In case the tappet-wire is passed transversely across the planter, as in some machines, only one set of levers, A, and one bar, E, will be used; but in case the wire passes along 70 the side of the planter, then a set of the devices will be required on each side thereof.

Having thus described my invention, what I claim as new, and desire to secure by Letters Patent, is—

In combination with the shaft B, having radial forked levers on one end and radial cams on its other end, the oscillating bar E, having a slot with grooves f f' f'' f''' in its side walls, substantially as and for the purpose specified. 80

In testimony whereof I affix my signature in presence of two witnesses.

LORENZO D. BENNER.
